UNITED STATES PATENT OFFICE.

FERDINAND PORSCHE, OF WIENER-NEUSTADT, AUSTRIA-HUNGARY.

DESIGN FOR AN AUTOMOBILE-HOOD.

43,015.

Specification for Design.

Patented Sept. 10, 1912.

Application filed June 3, 1912. Serial No. 701,459. Term of patent 7 years.

To all whom it may concern:

Be it known that I, FERDINAND PORSCHE, a subject of the Empire of Austria-Hungary, residing at Wiener-Neustadt, Austria-Hungary, have invented a new, original, and ornamental Design for Automobile-Hoods, of which the following is a specification, reference being had to the accompanying drawings, forming a part thereof.

Figure 1 is side elevation of an automo-

bile-hood, showing my new design; Fig. 2 is a plan view of Fig. 1, and Fig. 3 is a front elevation of Fig. 1.

I claim—

The ornamental design for an automobile hood as shown.

FERDINAND PORSCHE.
